UNITED STATES PATENT OFFICE

JEAN MATHIEU MARIE ARTHUR STEURS, OF VILVORDE, BELGIUM, ASSIGNOR TO
SOCIÉTÉ ANONYME MANUFACTURE D'APPAREILS GRAISSEURS, OF VILVORDE,
BELGIUM

LUBRICATING PAD

Application filed January 30, 1929, Serial No. 336,297, and in Belgium December 22, 1928.

The present invention relates to improvements in lubricating pads for axle-boxes and concerns more especially an improved lubricating pad for use on axle-boxes of railway 5 vehicles.

The primary object of this invention is to provide a very compact and elastic lubricating pad which shall be placed under the wheel axle in the axle-box and shall stay in 10 the right position without losing parts of wool or cotton as ordinarily happens with the waste cotton generally used for the same object.

Another object is to provide a lubricating 15 pad which will stand a long wear and which, to that effect, can be used successively on every side, owing to its great elasticity.

A further and most important object is to provide inside the pad an elastic frame 20 which shall keep inside the wool covering and shall not cut thru the covering, thus causing damage to the axle or to the axle-box.

A still further object is to provide an improved lubricating pad adapted to simplify 25 and facilitate the manufacture of the same.

These objects are accomplished by the improved construction of the lubricating pad hereinafter disclosed and illustrated by way of example in the accompanying drawings in 30 which:

Fig. 1 is a view of the inner frame.

Fig. 2 is a transverse section along the axis of the frame showing the complete pad.

Fig. 3 is a transverse section of the same, 35 perpendicular to the axis of the frame.

A thin sheet of steel 1, of proper dimensions is bent in shape of a cylinder, shown in Fig. 1. The two edges meeting are riveted to each other thru the holes 3 or can be secured otherwise. Other holes 4 are provided 40 along the edges of the cylinder and small projecting parts 2, formed integral with the sheet 1, are provided along the same edges and are somewhat bent towards the inside of the cylinder.

Around this elastic cylindrical frame 1 is secured, by means of wires 7 passing thru holes 4, a layer of a mixture of wool, cotton and hair or of very soft common felt, design- 45 nated by numeral 5 in Figs. 2 and 3, and

around this layer or felt is sewn a covering 6 made of wool or cotton or a mixture of both.

The intermediate layer 5 or felt, provides a suitable stuffing for the covering 6, and is protected from being cut by the sharp edges of the frame 1 by the projecting parts 2. By this stuffing the length of wear of the covering 6 is much increased.

The lubricating-pad thus constructed is introduced in the axle-box and is flattened under the journal which it lubricates for some length of time. When the covering on the side in contact with the journal is worn out another side of the same pad can be applied 35 against the journal.

Having now fully described my invention, what I claim and desire to secure by Letters Patent, is:

A lubricating pad for wheel-axles, especially for railway vehicles, designed for being inserted into the axle-box, under the journal, comprising a cylindrical metallic frame made of a single thin sheet of steel, means for securing the two edges thereof, a supporting and stuffing layer of very soft textile material, means for securing said layer onto said metallic frame, small projecting parts made integral with said frame and slightly bent towards the inside thereof for preventing said layer from being cut by the edges of said metallic frame, a covering made of wool and means for securing said covering over said stuffing layer, substantially as set forth.

In testimony whereof I have hereunto set my hand.

JEAN MATHIEU MARIE ARTHUR STEURS.
